DEVELOPING BLADE, DEVELOPING DEVICE, AND CARTRIDGE

BACKGROUND OF THE INVENTION

Field of the Invention

The present disclosure relates to a developing blade, a developing device, and a cartridge used in an image forming apparatus.

A cartridge described here includes at least one of developer, a developing roller, and a process unit and is detachably attachable to an image forming apparatus main body (hereinbelow, an apparatus main body). An image forming apparatus forms an image on a recording medium using an electrophotographic image forming process. An example of an image forming apparatus includes an electrophotographic copying machine, an electrophotographic printer (a light-emitting diode (LED) printer, a laser beam printer, etc.), a facsimile machine, and a word processor.

Description of the Related Art

An apparatus main body forms an electrostatic image by irradiating a photosensitive drum (an image bearing member) with light corresponding to image data. The apparatus main body supplies developer (hereinbelow, toner) to the electrostatic image from a developing roller (a developer bearing member) of a developing device and develops the electrostatic image as a toner image. The toner image is transferred from the photosensitive drum to a recording material such as recording paper by a transfer device. The toner image is fixed to the recording material by a fixing device, and thus a recorded image is formed. A developing device using toner uses a developing blade for regulating a layer thickness of the toner on the developing roller. In addition, a configuration is discussed for sealing toner by providing a sealing member between the developing roller and a developer container to prevent toner leakage from an end portion of the developing roller.

For example, Japanese Patent Application Laid-Open No. 2016-66077 describes a developing device which includes a developing roller, a developing blade, sealing members which are disposed on both end portions of the developing roller in an axis direction for sealing between the developing roller and a developer container, and a seal pressing member for pressing a side surface of the sealing member. In the developing device, the seal pressing member applies pressing force to the side surface of the sealing member in a direction toward a center of the developing device and deforms the sealing member to attach a side surface opposite to the pressed side of the sealing member to the developing blade.

Accordingly, the sealing members abut on the developing roller on the both end portions of the developing blade in the axis direction of the developing roller to prevent outflow of toner and toner leakage between the developing blade and the sealing member at the same time.

A metal blade of stainless steel and the like may be used as a developing blade in some cases. In this case, a blade thickness is generally 1 mm or less. Thus, it is discussed that the configuration in which the seal pressing member presses the side surface of the sealing member to attach the side surface of the sealing member opposite to the pressed portion to the developing blade as described in Japanese Patent Application Laid-Open No. 2016-66077 is applied to a developing blade using metal. However, when a thin metal blade is used, it was found that the sealing member disposed on a longitudinal end portion was deformed and crawled under the developing blade, and the sealing member was

2

brought into contact with a back surface opposed in a thickness direction to a front surface abutting on the developing roller. The sealing member is brought into contact with the developing blade and urges the developing blade toward the developing roller, and thus an abutting pressure is increased between the developing blade and the developing roller, and a failure of toner circulation is caused. Accordingly, there is a possibility that the toner melts and adheres to the developing blade and causes an image defect.

SUMMARY OF THE INVENTION

According to an aspect of the present invention, a developing device includes a developer bearing member configured to bear developer on a surface thereof, a developer container configured to contain the developer and rotatably support the developer bearing member, wherein the developer is supplied from the developer container to the developer bearing member, a regulating blade including a plate-like elastic portion, configured to regulate a thickness of a layer of the developer born on a surface of the developer bearing member, wherein a one end portion of the plate-like elastic portion is in contact with the developer bearing member, and the other end portion of the plate-like elastic portion is supported by the developer container in a direction orthogonal to a rotation axis direction of the developer bearing member, an elastic seal provided to be compressed between the developer bearing member and the developer container in an area of the developer container outside of the regulating blade in the rotation axis direction, configured to seal a gap between the developer bearing member and the developer container, and a pressing member configured to press the elastic seal so that an end surface of the elastic seal is brought into contact with an end surface of the plate-like elastic portion in the rotation axis direction, wherein the plate-like elastic portion includes a metal plate, a second projection projecting, in a direction approaching the developer bearing member, from a second surface of the metal plate that is provided on the one end portion side and faces the developer bearing member, and a first projection projecting, in a direction away from the developer bearing member, from a first surface opposite to the second surface of the metal plate on the one end portion side, and a projecting amount of the first projection from the metal plate is greater than a projecting amount of the second projection in a state in which the developer bearing member is not disposed, and wherein a top surface of the second projection is in contact with the surface of the developer bearing member, and an end surface of the first projection in the rotation axis direction is in contact with an end surface of the elastic seal in the rotation axis direction.

Further features of the present disclosure will become apparent from the following description of exemplary embodiments with reference to the attached drawings.

BRIEF DESCRIPTION OF THE DRAWINGS

FIG. 1 is a cross-sectional view of a longitudinal end portion of a developing blade according to an exemplary embodiment.

FIG. 2 is a cross-sectional view of an image forming apparatus main body and a process cartridge of an image forming apparatus according to the present exemplary embodiment.

FIG. 3 is a cross-sectional view illustrating a configuration of a developing device unit according to the present exemplary embodiment.

FIGS. 4A to 4C are perspective views illustrating a configuration of a developing cartridge according to the present exemplary embodiment.

FIGS. 5A to 5C are cross-sectional views near the developing blade of the developing cartridge in a direction orthogonal to a longitudinal direction according to the present exemplary embodiment.

FIG. 6 is a perspective view illustrating a configuration of a first sealing member according to the present exemplary embodiment.

FIGS. 7A and 7B are top views illustrating a configuration of a longitudinal end portion of the developing device according to the present exemplary embodiment.

FIG. 8 is a cross-sectional view of the longitudinal end portion of the developing device in a direction orthogonal to the longitudinal direction according to the present exemplary embodiment.

FIG. 9 is a cross-sectional view of a longitudinal end portion of a developing blade according to a modification of the present exemplary embodiment.

DESCRIPTION OF THE EMBODIMENTS

A cartridge and an image forming apparatus according to the present disclosure are described with reference to the attached drawings. A laser beam printer main body, and a drum cartridge and a developing cartridge which are detachably attachable to the laser beam printer main body are respectively described as an example of an image forming apparatus and cartridges. In following descriptions, a longitudinal direction of the drum cartridge is a direction (a rotation axis direction) parallel to a rotation axis L1 of a photosensitive drum (an image bearing member), and a longitudinal direction of the developing cartridge is a direction (a rotation axis direction) parallel to a rotation axis L0 of a developing roller. The rotation axis L1 and the rotation axis L0 are in a direction intersecting with a conveyance direction of a recording medium. Further, a transverse direction of the drum cartridge is a direction substantially orthogonal to the rotation axis L1 of the photosensitive drum, and a transverse direction of the developing cartridge is a direction substantially orthogonal to the rotation axis L0 of the developing roller. According to the present exemplary embodiment, a direction for attaching and detaching the drum cartridge and the developing cartridge to and from the laser beam printer main body is the transverse direction of each cartridge. Reference numerals in the descriptions are used for referring to the drawings and do not restrict the configuration.

(1) Entire Description of Apparatus Main Body

An entire configuration of an apparatus main body is described with reference to FIG. 2. FIG. 2 is a cross-sectional view illustrating the apparatus main body. The apparatus main body illustrated in FIG. 2 forms an image using toner t on a recording medium 2 by an electrophotographic image forming process according to image information transmitted from an external device such as a personal computer. An example of the recording medium includes recording paper, label paper, an overhead projector (OHP) sheet, and a cloth. An apparatus main body A1 includes a photosensitive drum 10, an optical unit 1 for forming an electrostatic latent image on the photosensitive drum 10, a developing unit for forming a toner image by developing the electrostatic latent image, a transfer unit for transferring the toner image to the recording medium 2, and a fixing unit 5 for fixing the toner image to the recording medium 2. The photosensitive drum 10 is configured as a

drum cartridge C so that a user can attach and detach the drum cartridge C to and from the apparatus main body A1, and similarly, the developing unit is configured as a developing cartridge B1 so that a user can attach and detach the developing cartridge B1 to and from the apparatus main body A1.

(2) Configuration of Developing Cartridge B1

Next, the electrophotographic image forming process is described with reference to FIG. 3. FIG. 3 is a cross-sectional view illustrating the developing cartridge B1 and the drum cartridge C. As illustrated in FIG. 3, the developing cartridge B1 includes a developer container 16 provided with a developing roller 13 as a developer bearing member and a developing blade 15.

The developer container 16 includes a toner containing unit 16a storing the toner t, a developing chamber 16c in which the developing roller (a developer bearing member) 13 and the developing blade (a regulating blade) 15 are arranged, and an opening portion 16b connecting the toner containing unit 16a and the developing chamber 16c. Thus, a toner conveyance member 17 rotatably provided to the toner containing unit 16a rotates in a direction of an arrow X17, so that the toner t stored in the toner containing unit 16a can be fed from the opening portion 16b to the developing chamber 16c. The developing chamber 16c is provided with the developing roller 13 constituted of a shaft portion incorporating a magnet roller 12 and a rubber portion which is rubber covering a circumferential surface of a center portion in the longitudinal direction of the shaft portion 13e (see FIG. 3). The shaft portion 13e is formed with an elongate cylinder made of a conductive member such as aluminum in which the center portion is covered with the rubber portion 13d in the longitudinal direction (see FIG. 3). The developing roller 13 can draw the toner t in the developing chamber 16c to a surface of the developing roller 13 by magnetic force of the magnet roller 12. The developing blade 15 is disposed in the developing chamber 16c so as to triboelectrically charge the toner t drawn to the surface of the developing roller 13 and regulate a layer thickness on the circumferential surface of the developing roller 13.

(3) Configuration of Drum Cartridge C

As illustrated in FIG. 3, the drum cartridge C includes a cleaning frame 21 provided with the photosensitive drum 10, a charging roller 11, and the like.

The drum cartridge C includes the photosensitive drum 10 rotatably supported and the charging roller 11 urged and brought into contact with the photosensitive drum 10 in the cleaning frame 21. The photosensitive drum 10 has a configuration in which a photosensitive member is disposed on a circumferential surface of a cylindrical body made of metal and the like, and can form an electrostatic latent image on a surface of the photosensitive member, namely the photosensitive drum 10. The charging roller 11 has a configuration in which an elastic member such as a foam is formed on a circumferential surface of a core metal and can uniformly charge the surface of the photosensitive drum 10 by a voltage applied from the apparatus main body A1. According to the present exemplary embodiment, the charging roller 11 is driven and rotated with respect to rotation of the photosensitive drum 10. More specifically, the surface of the photosensitive drum 10 is uniformly charged by the charging roller 11, and then an electrostatic latent image can be formed on the surface of the photosensitive drum 10 by a laser beam L from the optical unit 1 disposed in the apparatus main body A1.

(4) Description of Electrophotographic Image Forming Process

In the image forming apparatus, an image is formed on the recording medium 2 as described below.

First, the surface of the photosensitive drum 10 is uniformly charged by the charging roller 11 applied with a voltage from the apparatus main body A1. The charged photosensitive drum 10 is irradiated with the laser beam L corresponding to image information from the optical unit 1, and an electrostatic latent image corresponding to the image information is formed on the photosensitive drum 10. The developing roller 13 applied with the voltage from the apparatus main body A1 is rotated in a rotation direction X5 in a state in which the developing roller 13 is in contact with the photosensitive drum 10, thus the electrostatic latent image is developed by the toner t supplied to a development area of the photosensitive drum 10, and a toner image is formed on the surface of the photosensitive drum 10.

The developing roller 13 applied with the voltage from the apparatus main body A1 is rotated in the rotation direction X5 in the state in which the developing roller 13 is in contact with the photosensitive drum 10, so that the toner t is supplied to the development area of the photosensitive drum 10.

On the other hand, the recording medium 2 stored in a sheet feed tray 4 is regulated by a sheet feeding roller 3a and a separating pad 3b in pressure contact with the sheet feeding roller 3a and separated one by one in synchronization with formation of the toner image. A transfer roller 6 as the transfer unit is urged to contact the surface of the photosensitive drum 10 and forms a transfer nip portion 6a with the photosensitive drum 10. The recording medium 2 is conveyed by the conveyance guide 3d to the transfer nip portion 6a formed by the transfer roller 6 and the photosensitive drum 10 and passes through the transfer nip portion 6a. At that time, the transfer roller 6 is applied with a voltage having a polarity opposite to that of the toner image from the apparatus main body A1, and accordingly, the toner image formed on the surface of the photosensitive drum 10 is transferred to the recording medium 2.

The recording medium 2 on which the toner image is transferred is regulated by a conveyance guide 3f and conveyed to the fixing unit 5. The fixing unit 5 includes a driving roller 5a and a fixing roller 5c incorporating a heater 5b. The recording medium 2 is applied with heat and pressure when passing through a nip portion 5d formed by the driving roller 5a and the fixing roller 5c, and thus the toner image transferred to the recording medium 2 is fixed to the recording medium 2. Accordingly, an image is formed on the recording medium 2. Subsequently, the recording medium 2 is conveyed by a discharging roller pair 3g and discharged to a discharge portion 3h. Thus, the image formation on the recording medium 2 is completed.

(5) Toner Seal Configuration of Developing Cartridge

Next, an outline of a toner seal configuration of the developing cartridge B1 is described with reference to FIGS. 4A to 4C and FIGS. 5A to 5C. FIGS. 4A to 4C are exploded views illustrating the configuration of the developing cartridge B1. FIGS. 5A to 5C are cross-sectional views in a direction orthogonal to a rotation axis of the developing roller 13. FIG. 5A is the cross-sectional view when the developing blade 15 is assembled to the developer container 16, FIG. 5B is the cross-sectional view when the developing roller 13 is assembled to the developer container 16, and FIG. 5C is an enlarged view of an elastic resin member 15c.

As illustrated in FIGS. 4A to 4C, the developing cartridge B1 includes the developer container 16, the developing

blade 15, a driving side development bearing 36, a non-driving side development bearing 46, the developing roller 13, a first sealing member 51, a second sealing member 57, and a third sealing member 58.

The driving side development bearing 36 includes a fitting portion 36d, a support portion 36b, and a seal pressing portion 36a, and the non-driving side development bearing 46 includes a fitting portion 46d, a support portion 46b, and a seal pressing portion 46a. The driving side development bearing 36 and the non-driving side development bearing 46 are assembled so as to sandwich the developer container 16 therebetween in such a manner that the fitting portion 46d engages with a second positioning hole 16m of the developer container 16, and the fitting portion 36d engages with a first positioning hole 16l of the developer container 16. Further, a non-driving side end portion 13g of the developing roller 13 and a driving side end portion 13a of the developing roller 13 are respectively rotatably supported by the support portion 46b and the support portion 36b.

The developing blade 15 is a plate member and fixed to the developer container 16 by screws 52 and 53. The developing blade 15 includes a conductive support member 15a made of sheet metal, an flexible elastic member 15b supported by the support member 15a on a fixing end portion 15b2 to have a cantilever structure, and the elastic resin member 15c disposed on a free end side of the elastic member 15b. More specifically, a driving side end portion 15a1 of the support member 15a is fixed to a third fixing surface 16g of the developer container 16 by the screw 52 on a driving side in the longitudinal direction, and a non-driving side end portion 15a2 of the support member 15a is fixed to a fourth fixing surface 16h of the developer container 16 by the screw 53 on a non-driving side in the longitudinal direction. According to the present exemplary embodiment, a metal plate (stainless steel (SUS) plate) is used as the elastic member 15b which is fixed to the support member 15a by welding a fixing end portion 15b2 by an yttrium aluminum garnet (YAG) laser. The elastic resin member 15c is configured to cover a first surface 15b11 and a second surface 15b22 of a free end portion 15b1 of the elastic member 15b. The elastic resin member 15c includes a top surface 15c1 being in contact with the developing roller 13, a second projection 15c2 including the top surface 15c1, and a first projection 15c3 projecting to a direction opposite to the second projection 15c2. The elastic resin member 15c has a base layer 15e on both of the first surface 15b11 and the second surface 15b22 of the elastic member 15b. The first projection 15c3 and the second projection 15c2 included in the elastic resin member 15c are projected more than the base layer 15e. In other words, when the elastic member 15b provided with the elastic resin member 15c is regarded as a plate-like elastic portion (15b and 15c), the developing blade 15 has a following configuration. The elastic resin member 15c which is a one end portion of the plate-like elastic portion (15b and 15c) is in contact with the developing roller 13, and another end portion thereof is supported by the support member 15a in a direction orthogonal to the rotation axis direction of the developing roller 13.

Further, the plate-like elastic portion (15b and 15c) includes the first projection 15c3 and the second projection 15c2. The second projection 15c2 projects from the second surface (15b22) of the elastic member 15b facing the developing roller 13 toward a direction approaching the developing roller 13. The first projection 15c3 projects from the first surface (15b11) on an opposite side of the second surface of the elastic member 15b toward a direction away from the developing roller 13. A projecting amount L1 of the

first projection **15c3** from the elastic member **15b** is greater than a projecting amount **L2** of the second projection **15c2** in a state in which the developing roller **13** is not disposed. It is desirable that the projecting amount **L1** of the first projection **15c3** is 500 μm or greater. It is desirable that the projecting amount **L2** of the second projection **15c2** is 100 to 300 μm .

The second projection **15c2** projects so as to have a step portion that forms a gap between the developing roller **13** on an upstream side of a rotation direction of the developing roller **13** and the developing blade **15**. The second projection **15c2** abuts on the developing roller **13**, thus a peak value of an abutting pressure between the developing blade **15** and the developing roller **13** is increased, and the toner is convected on an upstream side of the second projection **15c2** so as to improve image quality. Specifically, the developing roller **13** abuts on a top surface **15c1** of the developing blade **15** while bending the elastic member **15b** as illustrated in FIGS. 5A to 5C. It is configured that a predetermined contact pressure acts on a contact region between the top surface **15c1** of the elastic member **15b** and the developing roller **13** when the elastic member **15b** is bent.

In addition, in the developer container **16**, the developing roller **13** is provided with the first sealing members **51** as elastic sealing members on the respective end portions on a driving side and a non-driving side to suppress outside leakage of the toner, and the first sealing members **51** seal between the developing roller **13** and the developer container **16** (FIG. 4A). The first sealing member **51** is disposed to be compressed between the developing roller **13** and the developer container **16** and seals a gap therebetween in an area outside of the developing blade **15** of the developer container **16** with respect to the rotation axis direction of the developing roller **13**. As illustrated in FIG. 6, the first sealing member **51** is constituted of a plurality of layers, more specifically, a surface layer **51d**, an intermediate layer **51c**, an adhesive layer **51f** adhering the surface layer **51d** and the intermediate layer **51c**, and a pasting layer **51g** fixing the intermediate layer **51c** to the developer container **16**. The surface layer **51d** includes a base fabric **51d2** and pile yarns **51d1** rising from the base fabric **51d2**. The pile yarn **51d1** may include a synthetic fiber such as polyethylene, polypropylene, polyester, nylon, acrylic resin, and polyethylene terephthalate, a half-synthetic fiber cotton such as rayon, a natural fiber such as cotton, combinations of these fibers, and twisted yarns. The base fabric **51d2** includes polyester and the like as a material thereof and is formed as a knit fabric and a woven fabric. The base fabric **51d2** is impregnated with a resin adhesive to fix the pile yarn **51d1** so as not to fall out from the base fabric **51d2**. The intermediate layer **51c** is a cushion layer formed by an elastic member and synthetic resin foam made from polyurethane and the like. The first sealing member **51** is compressed and disposed between the developing roller **13** and the developer container **16** in such a manner that the pasting layer **51g** is pasted on a first fixing surface **16d** and a second fixing surface **16e** of the developer container **16**. Accordingly, the developer container **16** is configured to prevent the toner from leaking from both ends in the longitudinal direction of the developing roller **13**.

In addition, the developer container **16** is provided with the second sealing member **57** made from an elastomer resin and the third sealing member **58** made from a flexible sheet. The second sealing member **57** is formed by injection molding with respect to the developer container to contact the respective first sealing members **51** between the first sealing members **51** arranged on the both ends in the

longitudinal direction. The second sealing member **57** seals between the developer container **16** and the support member **15a** and can prevent leakage of the toner when the developing blade **15** is attached to the developer container **16**. On the other hand, the third sealing member **58** is disposed along the axis direction of the developing roller **13** in such a manner that a one end side **58a** in a transverse direction is fixed to a fifth fixing surface **16j** of the developer container **16** by a joining unit such as a two-sided adhesive tape. Further, another end side of the third sealing member **58** in the transverse direction projects from the fifth fixing surface **16j** to be in contact with the assembled developing roller **13** and thus seals a gap extending in the longitudinal direction formed between the developer container **16** and the developing roller **13**. In a state in which the developing roller **13** is assembled, the third sealing member **58** is urged by the developing roller **13** and pressed to the first sealing member **51**. Accordingly, the first sealing member **51** and the third sealing member **58** are in contact tightly with each other without a gap to prevent the toner from leaking from a gap between the developer container **16** and the developing roller **13**.

(6) Seal Configuration of Longitudinal End Portion of Developing Blade

A detail configuration of a seal of a longitudinal end portion of the developing blade **15** in the developing cartridge **B1** is described with reference to FIG. 1 and FIGS. 7A and 7B. A non-driving side is described as an example, however, a driving side has the same configuration. The non-driving side development bearing **46** corresponds to the driving side development bearing **36**, and the seal pressing portion **46a** corresponds to the seal pressing portion **36a**. FIG. 1 illustrates a periphery and a cross section of the first sealing member **51**. FIGS. 7A and 7B are enlarged top views of a one end portion of the developing blade **15** in the longitudinal direction which illustrates before and after assembly of the non-driving side development bearing **46**. FIG. 7A is the top view illustrating a state before the non-driving side development bearing **46** is assembled, and FIG. 7B is the top view illustrating a state after the non-driving side development bearing **46** is assembled.

As illustrated in FIG. 7A, in a state in which the developing blade **15** is attached to the developer container **16** provided with the first sealing member **51** and the second sealing member **57**, a gap is formed between surfaces of the developing blade **15** and the first sealing member **51** facing each other. Thus, according to the present exemplary embodiment, the non-driving side development bearing **46** (a seal pressing member) is provided with the seal pressing portion **46a**. The seal pressing portion **46a** is configured to urge the first sealing member to the developing blade **15** when the non-driving side development bearing **46** is attached from the longitudinal end portion toward a center portion of the developer container **16** (an F direction in FIGS. 4A to 4C). In other words, the non-driving side development bearing **46** presses the first sealing member **51** so that an end surface (a side surface) of the first sealing member **51** is brought into contact with an end surface of the plate-like elastic portion (**15b** and **15c**) in the rotation axis direction of the developing roller **13**. Specifically, an outside end surface **51a** of the first sealing member **51** is urged by the seal pressing portion **46a** by force **F1**, and an inside end surface **51b** opposed to the outside end surface **51a** in the longitudinal direction is brought into contact with a longitudinal end surface of the developing blade **15**. Thus, a gap is suppressed from being formed between the developing blade **15** and the first sealing member **51**. Accordingly, when

the developing blade 15 is brought into contact with a circumferential surface of the developing roller 13 to form a toner layer on the developing roller 13, the toner t which is scraped off by the second projection 15c2 of the developing blade 15 and moved in the longitudinal direction can be suppressed from leaking to the outside from the gap.

According to the present exemplary embodiment, an end surface shape of the developing blade 15 in the longitudinal direction is formed to have the first projection 15c3 projected from a surface opposed to a surface on which the second projection 15c2 including the top surface 15c1 is disposed as illustrated in FIG. 5C. In other words, when the seal pressing portion 46a presses the first sealing member 51, a width in a thickness direction of the developing blade 15 in contact with the first sealing member 51 becomes larger at an edge portion on a free end side of the developing blade 15. Thus, the first sealing member 51 can avoid crawling under the developing blade 15 without causing the inside end surface 51b of the first sealing member 51 to contact a side surface of the developing blade 15 facing outside in the longitudinal direction. Accordingly, the present exemplary embodiment can suppress an image defect caused by defective toner regulation which occurs in such a manner that the toner melts and adheres the top surface 15c1 by urging force from the developing blade 15 to the developing roller 13 by the first sealing member 51, and a gap is formed between the developing blade 15 and the developing roller 13.

When a pressing surface 46a1 presses the outside end surface 51a of the first sealing member 51 in a direction of an arrow F, the surface layer 51d of the first sealing member 51 is moved in the direction of the arrow F, whereas the pasting layer 51g is fixed to the developer container 16 and does not move. In the first sealing member 51, the base fabric 51d2 has a configuration in which the knit fabric or the woven fabric is impregnated with the resin adhesive to prevent the pile yarn 51d1 from falling out from the base fabric 51d2, so that the base fabric 51d2 is the hardest compared to other layers and is hardly deformed. According to the present exemplary embodiment, the seal pressing portion 46a urges the outside end surface 51a including an end surface of the base fabric 51d2, while the inside end surface 51b not including the end surface of the base fabric 51d2 is brought into contact with the developing blade 15 (FIG. 8). Accordingly, the urging force of the developing blade 15 by the first sealing member 51 is regulated so as not to be excessive. On the other hand, when the urging force of the first sealing member 51 to the developing blade 15 is increased, a thickness N3 of the first projection 15c3 is thickened compared to a thickness N4 of the surface layer 51d to the base fabric 51d2 of the first sealing member 51 as illustrated in FIG. 9. Further, the seal pressing portion 46a urges the outside end surface 51a including the end surface of the base fabric 51d2, and the inside end surface 51b including the end surface of the base fabric 51d2 is brought into contact with the developing blade 15. Thus, it may be configured that a first contact portion 57a1 is urged by force F2 approximately equal to the force F1 urging the first sealing member 51 by the seal pressing portion 46a (F1≈F2). In addition, hardness of the surface layer 51d may be appropriately adjusted to make the first projection 15c3 bite into the surface layer 51d, and thus seal performance may be improved. The present exemplary embodiment has a configuration for improving the seal performance in which the first sealing member 51 wraps around the first projection 15c3 for a distance M2 in the longitudinal direction to an

extent not to increase force urging the developing blade 15 to the developing roller 13 by the first sealing member 51.

According to the present exemplary embodiment, the first projection 15c3 is arranged on a position to be symmetrical to the second projection 15c2 with respect to the elastic member 15b. Accordingly, a deformation for bending inside of the longitudinal direction which occurs when the first projection 15c3 is urged by the first sealing member 51 can be suppressed compared to when the first projection 15c3 is arranged on the free end side of the developing blade 15. Thus, the developing blade 15 can abut on the developing roller 13 more uniformly in the longitudinal direction. It is desirable that the first projection 15c3 overlaps with the second projection 15c2 in a direction orthogonal to the rotation axis direction when viewed from the rotation axis direction of the developing roller 13. It is desirable that the first projection 15c3 is disposed in an area excluding an edge of the free end portion 15b1 of the elastic member 15b. In addition, the present exemplary embodiment can suppress the first sealing member 51 from crawling under the developing blade 15 more satisfactorily compared to when the first projection 15c3 is arranged on a fixing end side of the developing blade 15. Further, according to the present exemplary embodiment, a protrusion having a rectangular shape when viewing the first projection 15c3 from the outside in the longitudinal direction is provided only on the longitudinal end portion. However, the first projection 15c3 is not limited to the above-described configuration and may include a protrusion having a dome shape or a trapezoid shape viewed from the outside in the longitudinal direction. Further, a protrusion may be disposed along an entire area in the longitudinal direction of the elastic member 15b or may be formed by pasting a member in the longitudinal end portion of the blade. In addition, according to the present exemplary embodiment, the configuration is described in which protrusions to be the first projections 15c3 are provided on end surface shapes located on the both ends in the longitudinal direction of the developing blade 15. However, any configuration can be adopted as long as it can prevent the first sealing member 51 from crawling under the developing blade 15. Thus, it may be configured that an end surface of the first projection 15c3 is located inside than the elastic member 15b and an end surface of a portion covering the elastic member 15b of the elastic resin member 15c in the longitudinal direction in a range in which the end surface of the first projection 15c3 is in contact with the first sealing member 51.

Unless otherwise specifically described, the scope of the present disclosure is not limited only to functions, materials, shapes, relative arrangement, and the like of the components described in the present exemplary embodiment. In addition, the same effect can be obtained by replacing the above-described hardness with Young's modulus and buckling strength.

While the present disclosure has been described with reference to exemplary embodiments, it is to be understood that the disclosure is not limited to the disclosed exemplary embodiments. The scope of the following claims is to be accorded the broadest interpretation so as to encompass all such modifications and equivalent structures and functions.

This application claims the benefit of Japanese Patent Application No. 2017-142025, filed Jul. 21, 2017, which is hereby incorporated by reference herein in its entirety.

What is claimed is:

1. A developing device comprising:
a developer bearing member configured to bear developer on a surface thereof;

11

a developer container configured to contain the developer, that is to be supplied to the developer bearing member; a regulating blade including an elastic portion, configured to regulate a thickness of a layer of the developer borne on the surface of the developer bearing member, wherein one end portion of the elastic portion, in an orthogonal direction orthogonal to a rotation axis direction of the developer bearing member, is in contact with the developer bearing member, and the other end portion of the elastic portion in the orthogonal direction is supported by the developer container; 5 an elastic seal provided so as to be compressed between the developer bearing member and the developer container in an area of the developer container outside of the regulating blade in the rotation axis direction, configured to seal a gap between the developer bearing member and the developer container; and a pressing member configured to press the elastic seal so that an end surface of the elastic seal in the rotation axis direction is in contact with an end surface of the elastic 10 portion in the rotation axis direction, wherein the elastic portion includes a metal plate, and first and second projections provided on the metal plate, the second projection projecting, in a direction approaching the developer bearing member, from a second surface of the metal plate that faces the developer bearing member, the first projection projecting, in a direction away from the developer bearing member, from a first surface opposite to the second surface of the metal plate, the first projection overlapping with the second projection when viewed in a direction in which the second projection projects, a projecting amount of the first projection from the first surface of the metal plate being greater than a projecting amount of the second projection from the second surface of the metal plate in a state in which the developer bearing member is not disposed, and 15 wherein a tip of the second projection is in contact with the surface of the developer bearing member, and an end surface of the first projection in the rotation axis direction is in contact with an end surface of the elastic seal in the rotation axis direction.

2. The developing device according to claim 1, wherein the first projection overlaps with the second projection in the orthogonal direction when viewed in the rotation axis direction. 45

3. The developing device according to claim 1, wherein the first projection is disposed in an entire area of the elastic portion in the rotation axis direction.

4. The developing device according to claim 1, wherein the first projection and the second projection are formed of a resin layer covering the metal plate. 50

5. The developing device according to claim 1, wherein the elastic seal includes a pile yarn and a base fabric on which the pile yarn is fixed, and wherein the side surface of the first projection is in contact with an end surface of the base fabric of the elastic seal in the rotation axis direction. 55

6. A developing device comprising:

a developer bearing member configured to bear developer on a surface thereof; a developer container configured to contain the developer, that is to be supplied to the developer bearing member; a regulating blade including an elastic portion, configured to regulate a thickness of a layer of the developer borne on the surface of the developer bearing member, wherein one end portion of the elastic portion, in an orthogonal direction orthogonal to a rotation axis direction

12

tion of the developer bearing member, is in contact with the developer bearing member, and the other end portion of the elastic portion in the orthogonal direction is supported by the developer container in a orthogonal direction orthogonal to a rotation axis direction of the developer bearing member;

an elastic seal provided so as to be compressed between the developer bearing member and the developer container in an area of the developer container outside of the regulating blade in the rotation axis direction, configured to seal a gap between the developer bearing member and the developer container; and

a pressing member configured to press the elastic seal so that an end surface of the elastic seal in the rotation axis direction is in contact with an end surface of the elastic portion in the rotation axis direction,

wherein the elastic portion includes a metal plate, and a resin layer covering a facing surface of the metal plate facing the developer bearing member and an opposite surface of the metal plate opposite to the facing surface, a part of the resin layer covering the opposite surface of the metal plate includes a base portion and a projecting portion arranged adjacent to the base portion in the orthogonal direction and having a thickness greater than that of the base portion so that the projecting portion projects further, in a direction away from the developer bearing member, than the base portion, and wherein an end surface of the projecting portion in the rotation axis direction is in contact with an end surface of the elastic seal in the rotation axis direction.

7. The developing device according to claim 6, wherein the projection is disposed in an area excluding an edge on the one end portion side of the metal plate.

8. The developing device according to claim 6, wherein the projection is disposed in an entire area of the elastic portion in the rotation axis direction.

9. The developing device according to claim 6, wherein the elastic seal includes a pile yarn and a base fabric on which the pile yarn is fixed, and

wherein the end surface of the projection in the rotation axis direction is in contact with an end surface of the base fabric of the elastic seal in the rotation axis direction.

10. A developing device comprising:
a developer bearing member configured to bear developer on a surface thereof;
a developer container configured to contain the developer, that is to be supplied to the developer bearing member; a regulating blade including an elastic portion, configured to regulate a thickness of a layer of the developer borne on the surface of the developer bearing member, wherein one end portion of the elastic portion, in an orthogonal direction orthogonal to a rotation axis direction of the developer bearing member, is in contact with the developer bearing member, and the other end portion of the elastic portion in the orthogonal direction is supported by the developer container;

an elastic seal provided so as to be compressed between the developer bearing member and the developer container in an area of the developer container outside of the regulating blade in the rotation axis direction, configured to seal a gap between the developer bearing member and the developer container; and

a pressing member configured to press the elastic seal so that an end surface of the elastic seal in the rotation axis direction is in contact with an end surface of the elastic portion in the rotation axis direction,

13

wherein the elastic portion includes a metal plate, and first and second projections provided on the metal plate, the second projection projecting, in a direction approaching the developer bearing member, from a second surface of the metal plate that faces the developer bearing member, the first projection projecting, in a direction away from the developer bearing member, from a first surface opposite to the second surface of the metal plate, a projecting amount of the first projection from the first surface of the metal plate being greater than a projecting amount of the second projection from the second surface of the metal plate in a state in which the developer bearing member is not disposed, wherein the elastic portion does not include, on the second surface of the metal plate, any projection projecting further than the second projection in the direction approaching the developer bearing member, and wherein a tip of the second projection is in contact with the surface of the developer bearing member, and an end surface of the first projection in the rotation axis

15

14

direction is in contact with an end surface of the elastic seal in the rotation axis direction.

11. The developing device according to claim **10**, wherein the first projection overlaps with the second projection in the orthogonal direction when viewed in the rotation axis direction.

12. The developing device according to claim **10**, wherein the first projection is disposed in an area excluding an edge on the one end portion side of the metal plate.

13. The developing device according to claim **10**, wherein the first projection is disposed in an entire area of the elastic portion in the rotation axis direction.

14. The developing device according to claim **10**, wherein the first projection and the second projection are formed of a resin layer covering the metal plate.

15. The developing device according to claim **10**, wherein the elastic seal includes a pile yarn and a base fabric on which the pile yarn is fixed, and wherein the side surface of the first projection is in contact with an end surface of the base fabric of the elastic seal in the rotation axis direction.
